UNITED STATES PATENT OFFICE.

ALFRED H. COWLES, OF SEWAREN, NEW JERSEY, ASSIGNOR TO THE ELECTRIC SMELTING & ALUMINUM COMPANY, OF SEWAREN, NEW JERSEY.

CHANNEL-FURNACE.

1,040,895.

Specification of Letters Patent.

Patented Oct. 8, 1912.

Application filed March 19, 1912. Serial No. 684,835.

To all whom it may concern.

Be it known that I, ALFRED H. COWLES, a citizen of the United States, and a resident of Searen, in the county of Middlesex and 5 State of New Jersey, have invented certain new and useful Improvements in Channel-Furnaces, of which the following is a specification.

My invention relates to furnaces of the 10 channel type.

It relates, moreover, to furnaces of this class that are provided with a track over which cars are fed into and through the furnace.

15 It relates particularly to ways and means for preventing deleterious gases that may be formed in the upper part of the furnace from penetrating below the car body and attacking the corrodible parts of the cars and 20 of the furnace and vestibule.

The object of the invention is to provide a furnace in which may be carried out my 25 process for making hydrochloric acid and alkali-silico-aluminate, set forth in my co-pending application Ser. No. 521,692, filed October 2d, 1910.

In carrying out my process it is necessary 30 that the spaces above and below the cars, or trucks, be isolated from each other, so that the injurious gases be kept in the upper part of the furnace, both while the cars are passing through the furnace and also while a new car is being introduced into the combustion chamber from the vestibule.

35 To carry out my present invention, I have devised several different methods, among which is the one forming the subject matter of the present application.

In the accompanying drawings is shown, 40 simply by way of example, and as illustrating the basic idea, means for generically carrying out my invention, and in the drawings:—Figure 1 is a general elevation of a channel or tunnel furnace, showing a vestibule and an air supply; Fig. 2 is a longitudinal section through the vestibule and a portion of the furnace; Fig. 3 is a vertical cross-section through the furnace, along the line $\alpha-\alpha$, of Fig. 2; Fig. 4 is a general longitudinal section through the furnace, show-

ing baffles, air supply, etc.; Fig. 5 shows the preferred form of baffles, and Fig. 6 shows the baffles attached to the moving car.

In the drawings: 1 is the furnace provided with the vestibule 2; 3 are rails on which 55 run cars 4; 5 is the transfer truck on which the cars 4 are brought into the vestibule over the tracks 6; 7 are rails on the top of the truck 5, on which rests the car 4, the rails 7 being on the same level with the rails 3 in 60 the furnace. When the cars 4 are in the furnace they divide it into two parts, one 8, above, the other 9, below the car body, and the lower part is generally provided with a car pit 10; 8^a, 9^a, and 10^a are corresponding 65 parts of the vestibule; 11 is a suction fan located at the top and near the entrance end of the furnace, for exhausting the hydrochloric acid, when my process is used.

12 is a blower, or equivalent device for 70 supplying gases, or air, under pressure to the portion of the furnace below the car body; 13 is the pipe supplied by the blower 12, and it is shown as located near the center of the furnace, dividing and running toward each end of the furnace; 14 are 75 baffles dividing the car pit into any desired number of sections. These baffles are preferably made of sheet metal mounted to swing as shown in Fig. 5, the lower part 80 of the baffle being weighted, as at 15. In Fig. 6 the baffles are shown as directly mounted on the car body. From the air supply pipe 13 there branch off short pipes 16, which communicate with each section of 85 the car pit formed by the baffles 14; 17 indicates valves or other means for controlling the pressure of the air (or gas) admitted to the various parts of the car pit; 18 are the pipes supplying the fuel, and 19 is a pipe 90 for blowing into the exit end air and steam; 20 indicates the material composing the charge; 21 are a series of curtains or baffles located in the upper part of the furnace and fitting quite closely to the load on the car 4 95 forming a practically sufficient seal for the gases in that part of the furnace; 23 is the door leading from the vestibule into the furnace proper, and 24, a means for opening and closing said door.

25 are sand seals into which dip metal sheets fastened to the sides of the transfer truck 5.

27 indicates the sand seals located along 5 the sides of the furnace, sealing the car pit from the upper portion of the furnace.

The ends of the cars should be made to fit together as tightly as possible, and, if necessary, an asbestos packing be attached to one 10 end of each car, to as effectually as is practicable prevent flow of gases upward and downward between the cars.

A furnace constructed according to this 15 invention may be used for several purposes, and can be varied in structure to a large degree without departing from the essence of my generic invention, which broadly stated consists in the process of an apparatus for preventing injurious gases in the furnace 20 from coming in contact with the corrodible portions of the furnace and the cars, while cars are being introduced into the vestibule or fed into the furnace.

As an example of the use of my improved 25 furnace, I will describe its application by me to the manufacture of hydrochloric acid and alkali-silico-aluminate. The charge mixture composed of clay, salt and carbon, in the proportions, say of 35% to 65% clay, 30 30% to 50%, alkali chlorid and 3% to 10% carbon, is loaded onto the transfer truck (resting on the car 4) and introduced into the vestibule. The door between the vestibule and the furnace being closed, the front 35 or outer door of the vestibule is raised and the transfer truck quickly introduced over the track 6. When the truck is fully within the vestibule, the front vestibule door is closed, completely sealing the vestibule from 40 the outer air. The door 23 is now raised and the car is pushed gradually into the furnace by the pusher 22, forcing forward the cars already introduced and the charge mixture on which is undergoing conversion. During 45 the time that the door 23 remains open, that is, during the time the car is being introduced, the curtains, or baffles, 21, lying close about the car and its charge, prevent any noticeable escape of gas from the portion 50 of the furnace into the vestibule, and the baffles 14 keep at will the gases below the cars from escaping into the vestibule. As the charge comes into the furnace it is subjected to the combustion gases and to steam 55 and air that is blown into the furnace against the direction of movement of the cars. The chemical reaction of the conversion transforms the charge into alkali-silico-aluminate and hydrochloric acid, this 60 latter being drawn off to an acid condensing system by the suction fan 11. The curtains 21 prevent the escape of the acid over and around the loaded cars. So long as this acid remains in the state of vapor and above

220° F. the iron of the cars and of the furnace is not attacked thereby. But should these vapors penetrate to the car pit and come into contact with iron relatively cool and become thereby condensed, such would be destroyed, if of iron or other corrodible 65 substances. It is to prevent this that I have arranged along the sides of the furnace the gas supply 13, tapping off into the spaces between two successive baffles, and I blow through this an air or gas supply, and I so 70 regulate the pressure thereof, say by the valves 17, that there is always a balance between the pressures above and below the cars, or else a slight excess pressure upward from below the cars, causing a slight leak 75 upward, but a downward leak is to be avoided.

I do not herein claim the process of making hydrochloric acid and alkali-silico-aluminate, as that forms the subject matter of 80 my copending application, Ser. No. 521,692.

What I claim, is:

1. A channel furnace having a combustion chamber through which trucks are adapted to be passed and means for maintaining the spaces above and below the trucks isolated from each other while introducing a fresh truck into the combustion chamber.

2. A furnace of the channel type having 95 a vestibule suitably sealed from the furnace proper and the outer air, said vestibule being provided with rails for supporting a transfer car, rails on the upper surface of the transfer car, a car carried by said rails, 100 in combination with a pusher penetrating the wall of the vestibule and adapted to impart to the car on the transfer car a gradual and uniform movement into and through the channel furnace.

3. A furnace of the channel type provided with a track, cars located on said track and dividing the furnace into two portions, one above and one below the car bodies, means for supplying gas to, and means for exhausting gas from the upper portion of the furnace, means for dividing the portion of the furnace below the cars into a series of separate sections extending throughout the length of the furnace, a gas supply connected with 115 each such sections, and means for separately regulating the gas supply to each section, so as to prevent the gases from passing from the upper to the lower portion of the furnace.

4. In a furnace of the channel type, a track, cars running on said track and dividing the furnace into upper and lower portions, a series of curtains at the entrance end of the furnace, and an exhaust fan located near the said entrance end, in combination with means for preventing gas passing from above to below the car bodies.

5. A channel furnace provided with a car track, cars resting on said track, a car pit, a series of movable baffles dividing the car pit into separate sections, and an adjustable means of gas supply connected with each section.

Signed at New York in the county of New

York and State of New York this 14th day of March A. D. 1912.

ALFRED H. COWLES.
